PAD HOLDERS

Joseph E. Fernly, Muskegon, Mich.

Application November 12, 1957, Serial No. 695,742

2 Claims. (Cl. 211—51)

My invention relates to pad holders and the like and more particularly to an improved pad holder having a supporting plate and a spring between which one or more pads or like articles may be retained.

A common difficulty in the use of coiled springs and similar elastic retaining means is that the ends thereof rapidly become permanently distorted and weakened from being stretched beyond the elastic limits due to bending over corners and catching on the edges of articles being inserted. This has been found to occur even when high quality, relatively strong coil springs are used, since the tension applied is unequal over its length and when casually handled such holders lose their ability to firmly hold the articles.

An object of my invention is to improve pad holders by providing an elastic retaining means which has longer than usual life.

Another object of the invention is to provide improved pad holders by constructing a supporting plate and an elastic retaining means carried thereby, said retaining means including an elastic member having at all times a length less than the width of the pad or article being held.

A further object of the invention is to construct an improved pad holder by providing a supporting plate and an elastic retaining member having an intermediate elastic member and arms at each end adapted to engage the edges of the pad or article being held.

Yet another object of the invention is to provide an improved pad holder by constructing a supporting plate and an elastic retaining member comprising an intermediate elastic member and end arms pivotally attached at their outer ends to the supporting structure.

For a more complete understanding of the invention, reference may be had to the accompanying drawing illustrating preferred embodiments of my invention in which like reference characters refer to like parts throughout the several views and in which:

Fig. 1 is a front elevational view of a preferred holder construction and a pad being retained by the spring.

Fig. 2 is a cross-sectional view taken substantially on the line 2—2 of Fig. 1.

Fig. 3 is a side elevational view of the pad holder of Fig. 1 but with another pad inserted.

Fig. 4 is a cross-sectional view taken substantially on the line 4—4 of Fig. 3.

Fig. 5 is a fragmentary cross-sectional view taken substantially on the line 5—5 of Fig. 1.

Fig. 6 is a fragmentary front elevational view of a modification of the retaining means of Fig. 1, and

Fig. 7 is a cross-sectional view taken substantially on the line 7—7 of Fig. 6.

In Fig. 1, the preferred pad holder is illustrated as comprising a supporting plate 10 having flanges 11 on each side thereof and a clamp member 12 or other attaching means. The particular holder shown is of a kind clamped to the handle-bar of a motorcycle and is used

by policemen for holding a traffic violations ticket pad 13 or other similar articles.

A coil spring 14 or other suitable elastic member is supported between two arms 15, which preferably comprise flat ribbed elements each having a piano hinge type end as shown in Fig. 5 for pivotal attachment to flange 11 by passing through a slot 16 provided in the flange 11. The spring 14 must be at all times shorter than the width of the pad 13, so that the edges of the pad will engage only with the arms 15, as shown in Fig. 2, the arms 15 pivoting upward so that the tension applied to the spring 14, which engages only the flat upper surface of the pad 13, is applied at all times along the straight longitudinal axis A of the spring 14. The arms 15 are preferably pivotally connected also to the ends of the spring 14.

A common expedient of those who use similar spring type holders is to lift the single pad 13 and insert another behind it; that is, between the first pad 13 and the plate 20 10, as illustrated in Fig. 3. If the spring 14 of the holder were to engage the edge of the first pad 13, this procedure would cause excessive stretching of the ends of the spring 14, and would ultimately result in failure of the spring 14 to retain the pads 13 in place. However, it is seen 25 that in the present construction, the edges of the pad 13 will slide up on the arms 15, which pivot relative to the flanges 11 and the spring 14, stretching or tensioning the spring only along the longitudinal axis A, as indicated in Fig. 4. Thus the spring 14 is never deformed 30 to weaken or bend it, and it will have a much longer life than if the arms 15 were not used.

In addition, the arms rather than the spring grip the edges of the pad, and the spring tension acting through the arms is concentrated against the edges of the pad 35 so that the pads are gripped more securely to prevent the likelihood of the pads becoming dislodged accidentally.

A less expensive modification of the invention is shown in Figs. 6 and 7, in which a spring 20 is provided with integral arm ends 21 which are pivotally secured to holes 40 22 provided in the flanges 11. The arms 21 in this case are to a small extent flexible, so as to bend over the edges of the pad 13 and still apply spring tension only along the axis A.

It will be apparent to one skilled in the art to which 45 the invention pertains that various changes and modifications may be made therein without departing from the spirit of the invention or the scope of the appended claims.

I claim:

50 1. A pad holder comprising a supporting plate and an elastic retaining means carried by said plate, said elastic retaining means comprising an elastic member and substantially non-elastic arms carried on opposite ends of said elastic member, each arm having a hinge portion pivotally secured to said plate, a second hinge portion pivotally secured to an end of said elastic member, and an intermediate portion adapted to engage only an edge of a pad inserted between said retaining means and said plate, said elastic member being adapted to engage only 55 the flat surface of said pad.

60 2. A pad holder comprising a supporting plate and an elastic retaining means carried by said plate, said elastic retaining means comprising an elastic member and substantially non-elastic arms carried on opposite ends of 65 said elastic member, each arm having a hinge portion pivotally secured to said plate, a second hinge portion pivotally secured to an end of said elastic member, and an intermediate portion adapted to engage only an edge of a pad inserted between said retaining means and said plate, said elastic member being adapted to engage only 70 the flat surface of said pad, said supporting plate comprising a substantially flat base member having spaced

upstanding flanges, said retaining means extending across the space between said flanges and the first mentioned hinge portions of said arms being pivotally attached to said flanges and operable to selectively pivot said arms upward away from said flat base member upon insertion of a pad, thereby only applying substantially longitudinal tension on said elastic member.
